(57) **CLAIM**

The ornamental designs for a fondue fork, as shown and described.

DESCRIPTION

FIG. 1 is a left side view of a fondue fork, according to a first embodiment;

FIG. 2 is a front view of a fondue fork, according to a first embodiment;

FIG. 3 is a back view of a fondue fork, according to a first embodiment;

FIG. 4 is a top view of a fondue fork, according to a first embodiment;

FIG. 5 is a bottom view of a fondue fork, according to a first embodiment;

FIG. 6 is a top perspective view of a fondue fork, according to a first embodiment;
FIG. 7 is a bottom perspective view of a fondue fork, according to a first embodiment;
FIG. 8 is a left side view of a fondue fork, according to a second embodiment;
FIG. 9 is a top perspective view of a fondue fork, according to a second embodiment;
FIG. 10 is a left side view of a fondue fork, according to a third embodiment;
FIG. 11 is a top perspective view of a fondue fork, according to a third embodiment;
FIG. 12 is a left side view of a fondue fork, according to a fourth embodiment;
FIG. 13 is a top view of a fondue fork, according to a fourth embodiment;
FIG. 14 is a top perspective view of a fondue fork, according to a fourth embodiment;
FIG. 15 is a left side view of a fondue fork, according to a fifth embodiment;

FIG. 16 is a top perspective view of a fondue fork, according to a fifth embodiment;
FIG. 17 is a left side view of a fondue fork, according to a sixth embodiment;
FIG. 18 is a top view of a fondue fork, according to a sixth embodiment;
FIG. 19 is a top perspective view of a fondue fork, according to a sixth embodiment;
FIG. 20 is a left side view of a fondue fork, according to a seventh embodiment;
FIG. 21 is a top view of a fondue fork, according to a seventh embodiment; and,
FIG. 22 is a top perspective view of a fondue fork, according to a seventh embodiment.
The right side of each embodiment is a mirror image of its left side.
Note that any broken line illustration of environmental structure in the drawing is not part of the design sought to be patented.
